AIR CONDITIONING APPARATUS

Arthur S. Locke, Philadelphia, Pa., assignor to
Baldwin-Southwark Corporation, a corpora-
tion of Delaware

Application December 29, 1933, Serial No. 704,422

18 Claims. (Cl. 62—129)

This invention relates generally to air conditioning apparatus of the type employing refrigerating mechanism and more particularly to an improved room cooler unit utilizing a condenser arranged for maximum condenser area in a relatively small space and for effecting air flow over the condenser to cool the same.

Various arrangements have heretofore been proposed to effect a relatively small self-contained room cooler unit utilizing a refrigerating mechanism having an air cooled condenser, but one difficulty with such a type of unit is the necessity for a relatively large condenser together with an adequate arrangement for effectively 15 cooling the condenser by air. It is further necessary not only to provide an efficient condenser of suitable capacity but also to keep the room space required for the unit at a minimum.

It is one object of my invention to provide an improved unit so constructed and arranged as to permit the use of a relatively large condenser together with means for effectively circulating outside cooling air over the condenser and for circulating room air over the evaporator while at the same time providing a relatively simple unit that is economical in manufacture and maintenance and requires minimum room space for a given capacity of the unit. In one aspect of the invention I accomplish the foregoing object by 25 having the condenser overlie both the outside air circulating means and the compressor with the air ducts so arranged that the outside air may efficiently flow transversely over the condenser such as from one side thereof to the other. In 30 a more specific aspect of the invention I provide a condenser placed in complete cooperation with an outside air duct through which condenser cooling air is conducted.

In a further specific aspect of the invention I 35 provide an improved unit having an outside air duct normally extending to a window, or other suitable opening in a room wall, with a condenser disposed directly within said duct, although in certain embodiments the condenser is also partially disposed within that portion of the unit located in the room.

A further object is to provide improved means for disposing of condensate in a unit of this kind, and in one specific aspect thereof I provide an improved float actuated motor-driven pump so arranged that condensate from the evaporator side of the unit will accumulate in such a manner and location that the pump may be effectively 45 actuated only at predetermined intervals to dis-

charge under pressure the condensate into the outside air stream.

A still further object is to provide an improved arrangement of condenser, evaporator, compressor and air circulating means so as to obtain advantages that will be observed from the disclosure herein. 5

Other objects and advantages will be more apparent to those skilled in the art from the following description of the accompanying drawings 10 in which:

Fig. 1 is a vertical transverse section through the unit embodying my improved features taken on the line 1—1 of Fig. 2;

Fig. 2 is a vertical section taken substantially on 15 the line 2—2 of Fig. 1;

Fig. 3 is a vertical sectional view through one form of unit;

Fig. 4 is a plan view thereof taken substantially on 20 the line 4—4 of Fig. 3;

Fig. 5 is a sectional view taken substantially on 25 the line 5—5;

Fig. 6 is a vertical transverse section of the modified form of unit;

Fig. 7 is a vertical longitudinal section taken on 30 the line 7—7 of Fig. 6;

Fig. 8 is a vertical longitudinal section taken on 35 the line 8—8 of Fig. 6;

Fig. 9 is a vertical section through a unit embodying my improved features including one 40 form of condensate disposal means;

Fig. 10 is an enlarged fragmentary view of the 45 condensate controlled motor-actuated pump.

In the particular embodiments of the invention which are disclosed herein merely for the purpose of illustrating certain specific forms among possible others that the invention might take, I have shown in Fig. 1 a self-contained unit having an elongated evaporator coil 1 disposed within a suitable vertical passageway 2 while a condenser 4 is disposed within a passageway 5. These elements may be supported in any suitable manner on a base 6 and preferably in spaced relation thereto to permit air circulating means to be disposed beneath the evaporator and condenser. 50

As shown in the longitudinal section of Fig. 2, the air circulating means includes a room air fan 7 for circulating air from the room, thence beneath the lower spaced edge of the cabinet 8 to the fan inlet 8. This air is then discharged 55 through preferably a spiral scroll 10 in a tangential direction as indicated at 11 to passage 2, whereupon the air flows vertically over evaporator 1 and through an outlet 12 to the room. To cool the condenser 4 by outside air, the unit is 55

placed preferably adjacent a window or opening 13 and outside air is drawn in through one part of a window duct 15 and thence preferably down over a vertical axis motor-compressor unit diagrammatically indicated at 16 to flow inwardly through an inlet 17 of a condenser blower or fan 18, the air thus being forced upwardly over condenser 4 and discharged to the outside atmosphere through another portion 19 of the window duct. The two blowers are preferably driven by a common motor 20 supported on base 6. If desired, the duct 5 may open directly into the space containing motor 20 and fan scroll 10 as the latter and its casing 2 are entirely closed 15 against admission of air except room air from beneath cabinet 9. However, if desired, the passage 5 may have a lower wall indicated by dotted lines 21.

The condenser 4 as shown in Fig. 1 is L-shaped 20 having its major portion disposed within passage 5, although a very substantial portion continues directly into the atmospheric duct 14. This condenser also extends over the compressor for the full length of the unit as noted from Fig. 2. The 25 portion of the condenser disposed over motor-compressor unit 16 is cooled by the inflowing air while the remainder of the condenser is cooled by the outflowing air. As a result of this particular arrangement, it is seen that the condenser when 30 formed as a unit (fins 22 holding all of the pipe coils together) can be completely supported by the walls of passage 5, although if necessary supplemental braces may extend from the unit laterally through the window duct to help support the 35 portion of the condenser therein.

To take care of the condensate, there is provided a series of longitudinal troughs 24 adapted 40 to collect condensate dripping down from evaporator 1, this condensate flowing through a pipe 25 to a similar set of troughs 26. The water is then entrained by the upward flowing condenser cooling air through passages 27. It will be noted 45 from Fig. 2 that the condensate troughs 26 are disposed only adjacent that portion of the condenser over which the outflowing air passes. It will of course be understood that evaporator 1 likewise extends for the full length of the unit 50 in the same manner as condenser 4, thereby taking full advantage of the space above the motor-compressor unit 16.

In the modification shown in Figs. 3, 4 and 5, I have provided, Fig. 4, a vertical axis motor-compressor unit 30 disposed within a suitably enclosed compartment 31 while adjacent thereto is 55 an evaporator compartment 32 in which is removably disposed an evaporator 33. Disposed immediately behind the motor-compressor unit and the evaporator, and extending for the full length of the unit is a condenser 34 located entirely within an atmospheric duct generally indicated at 35. This duct and condenser 34 may be supported in any suitable manner as by structural channels or beams generally indicated at 36, thereby to form the condenser as a self-contained 60 part of the unit.

To cool the condenser, vertical passages 37 and 38 extend for the full length of the unit except they are divided by a partition 39, this partition mating with any one of the rectangular shaped plate fins 40 of the condenser. Hence 65 outside air will flow inwardly through one-half of the condenser and down through passage 37, thence into the inlets 41 of a condenser fan 42, the air thence flowing upwardly through passage 38 and out over the other half of the con-

denser 34. Room air is circulated over evaporator 33 by a blower 44 whose rotor is shown in plan view at 45 in Fig. 5. In this arrangement it is seen that the same compact relation is maintained as in the preferred form in that the compressor and evaporator completely overlie the air circulating means including a common driving motor 47 therefor.

In the modification of Fig. 6, an evaporator 50 is disposed in a suitable passage 51 which has its lower end closed by a horizontal bottom plate 52. Room air enters around the cabinet or through suitable openings therein to flow laterally through openings 53 and 54 in the unit, thereby to be circulated upwardly over the evaporator 50 preferably by a pair of propeller fans 55 and 56, this air being discharged into the room through a suitable opening in the top of the cabinet. A condenser 58 is disposed entirely in a window duct 59 and supported as a self-contained part of the 20 unit by any suitable structural means such as a cantilever beam 60. Outside air is circulated over the condenser by a pair of fans 61 and 62 which are separated by a vertical partition 63, thereby causing outside air to be drawn inwardly 25 over one-half of the condenser by fan 62 and thence discharged downwardly along one side of partition 63 and thence upwardly on the other side thereof to be discharged outwardly over the other half of the condenser by fan 61. As a 30 result of this general arrangement, it is seen that ample space is left in the lower portion of the unit to house a horizontal motor-compressor unit generally indicated at 64. Also the outside air is adapted to flow over this unit as indicated 35 by the arrows in Fig. 8.

To dispose of the condensate in this improved form, I have provided a reciprocating piston pump generally indicated at 65 actuated by a suitable crankpin on the end of the vertical shaft 40 of fan 55. An inlet pipe 66 communicates with the bottom of plate 52 serving as a sump into which condensate will drip from evaporator 50 as the room air is dehumidified. The discharge side 67 of this pump conducts the moisture preferably to a point where the condensate will flow over the condenser 58, this being accomplished specifically by having the outlet end 68 terminate 45 preferably in the form of a jet-forming orifice directly in front of the discharge fan 61, whereby 50 the high velocity of air will spray the moisture over the hot surface of the condenser. Hence it is seen that the room air fan and condenser air fan are brought into functional cooperation in the disposition of the condensate. It will of 55 course be understood that the unit is supported upon a base 69.

In the modification shown in Fig. 9, an evaporator 75 and condenser 76 are arranged generally in the manner of Fig. 1. However, to collect and dispose of the condensate, the base 6' is provided with a depressed portion 77 to serve as a condensate collecting sump. To dispose of the condensate, there is provided a small electric motor 78 actuating any suitable pump 79 of either 65 the piston or gear type arranged with its suction pipe 80 extending into the sump 77 while its discharge pipe 81 leads up to adjacent the condenser 76 so that discharged water will be carried away by the outside air flowing over the condenser. 70 To automatically control the starting and stopping of this pump in accordance with the amount of condensate, there is provided preferably a mercury switch generally indicated at 83. This switch has lead wires 84 connected to terminals 75

within the tubular member 83, whereby a globule of mercury 85 may close or open said contacts. To effect actuation of this switch by the condensate, the switch is provided with an arm 86 pivotally supported at 87 to any suitable bracket 88. The free end of the mercury switch tube is provided with a cork collar or head 89 so as to permit the switch to float to its circuit-closing position shown in Fig. 10, thereby to actuate the motor. 10 Once the switch is closed, it will remain closed until the liquid level 90 has dropped to the point where the mercury globule 85 will flow to the other end of the tubular container, this position being shown in dotted lines. Hence it is seen that the use of this mercury switch in combination with the float permits the sump to be appreciably filled before the mercury will flow to the other end of the tube to close the contacts and yet when the contacts are once closed, the 20 switch will remain closed until the condensate is pumped out substantially entirely at which time the mercury tube will be in such an angular position as to permit the mercury globule to break its contacts.

25 From the foregoing disclosure of the several modifications, it is seen that I have provided an extremely compact arrangement of a condenser, evaporator and air circulating means together with a motor-compressor unit of the refrigerating system. It is also seen that the provision of the horizontally disposed condenser directly within the atmospheric duct permits full utilization of the space therein without any sacrifice of efficiency and also permits effective disposal 30 of the condensate as the air flow over that portion of the condenser in the atmospheric duct is better able to carry the moisture along in the air stream. In the vertical portion of the condenser, the air stream must be able to support not only 35 the weight of the water but also to have sufficient force to impart vertical movement thereto, whereas in the atmospheric duct portion of the condenser the air stream need only move the condensate horizontally without regard to supporting its weight.

40 It will of course be understood that various changes in details of construction and arrangement of parts may be made by those skilled in the art without departing from the spirit of the invention as set forth in the appended claims.

50 I claim:

1. An air conditioning unit comprising, in combination, an evaporator, means for circulating room air thereover, an atmospheric duct projecting rearwardly from said unit and adapted to communicate with the outside through a window or other suitable wall opening, a condenser disposed directly within said duct and forming a self-contained part of said unit, and means 55 for circulating outside air inwardly of said duct and over the condenser therein.

2. A self-contained air conditioning unit comprising, in combination, an evaporator, means for circulating room air thereover, an L-shaped condenser having one leg thereof projecting rearwardly from said unit, a window duct in which said condenser leg is disposed, and means 60 for circulating outside air over said condenser.

3. An air conditioning unit comprising, in combination, an evaporator, means for circulating room air thereover, a condenser having a portion overhanging the back side of said unit and extending directly rearwardly from within the same at the upper portion thereof, and means 65 for circulating outside air over said condenser.

including a window duct in which at least a portion of said condenser is disposed.

4. The combination set forth in claim 1 further characterized by the provision of means for carrying away condensate in the condenser air stream. 5

5. The combination set forth in claim 1 further characterized by the provision of means for discharging condensate over the surface of the condenser disposed within the window duct. 10

6. An air conditioning unit comprising, in combination, a base, a motor-compressor unit supported thereby, room air and outside air blowers also supported by said base, an evaporator, and an air cooled condenser supported above said outside air blower and compressor unit, whereby air flows upwardly and thence transversely of said evaporator and condenser. 15

7. A self-contained air conditioning unit comprising, in combination, a compressor, a condenser, an evaporator, means for constantly circulating room air over said evaporator and outside air over said condenser, a base for supporting said elements having a sump therein in which condensate is adapted to collect, a motor-driven pump for discharging said condensate into the stream of outside air, and a float actuated switch disposed in said sump for starting or stopping said motor automatically in accordance with predetermined levels of condensate in said sump 25 whereby the outside air stream continues to flow so as to be constantly operative to receive intermittently pumped condensate. 30

8. A self-contained air conditioning unit comprising, in combination, a base, an evaporator, 35 a condenser, means for constantly circulating room air over said evaporator and outside air over said condenser, means for collecting condensate from said evaporator, and a motor-driven float controlled pump for discharging condensate 40 over said condenser.

9. A self-contained air conditioning unit comprising, in combination, an evaporator, a vertical axis motor-driven propeller fan for circulating room air over said evaporator, a condenser, means for circulating outside air over said condenser including a window duct in which said condenser is at least partially disposed, and a pump driven from the lower end of said propeller fan motor shaft for discharging condensate to 45 the outside air. 50

10. The combination set forth in claim 9 further characterized in that said outside air circulating means includes a blower and the pump discharges directly into the air stream from said blower. 55

11. A self-contained air conditioning unit comprising, in combination, an evaporator, motor-driven propeller means for moving room air horizontally in the unit and turning the air so as to pass vertically over said evaporator, a condenser extending into the upper portion of the unit, and means for circulating outside air over said condenser and out through said upper portion of the unit. 60

12. A self-contained air conditioning unit comprising, in combination, an evaporator extending for substantially the full length of the unit, vertical axis motor-driven propeller fans for circulating room air from opposite sides of the unit and thence over said evaporator, a condenser disposed to the rear of said evaporator, and means for circulating outside air over said condenser to cool the same. 70

13. The combination set forth in claim 12 fur- 75

ther characterized in that a pair of propeller fans is provided to circulate room air from opposite ends of said unit and thence vertically over said evaporator in a vertical direction.

5 14. The combination set forth in claim 12 further characterized in that said evaporator and fan are supported in spaced relation to a base, and a motor-compressor unit is disposed beneath said evaporator and fan.

10 15. A self-contained air conditioning unit comprising, in combination, a base, an evaporator and air cooled condenser each extending substantially the full length of said unit and in spaced relation to said base, and air circulating means 15 and a motor-compressor unit disposed beneath said evaporator and condenser, whereby air flows upwardly and transversely of said condenser.

16. An air conditioning unit comprising, in combination, an evaporator, means for circulating room air thereover, an atmospheric duct projecting rearwardly from said unit and adapted to communicate with the outside atmosphere through a window or other suitable wall opening, a condenser disposed directly within said

duct and forming a self-contained part of said unit, and means for circulating outside air over the condenser therein.

17. A self-contained air conditioning unit comprising, in combination, a base having a sump 5 formed therein to collect condensate, an evaporator from which condensate flows to said sump, a condenser, means for circulating room air over said evaporator and outside air over said condenser, a motor driven pump for discharging condensate from said sump, and means for controlling the operation of said pump motor automatically in accordance with the liquid level in said sump.

18. An air conditioning unit comprising, in 15 combination, a base, a motor compressor unit supported thereby, outside air and room air blowers also supported by said base, an evaporator supported above said room air blower, and an air cooled condenser overlying both the outside air blower and compressor unit whereby air flows upwardly and also laterally relative to said condenser before flowing transversely thereover.

ARTHUR S. LOCKE.
